MIXING APPARATUS

Le Roy Eaby, Lancaster, Pa., assignor to Armstrong Cork Company, Lancaster, Pa., a corporation of Pennsylvania

Application October 31, 1945, Serial No. 625,791

22 Claims. (Cl. 259—6)

1

This invention relates to apparatus for mixing plastic materials and, in particular, to mixing apparatus adapted to handle relatively heavy, highly viscous mixes involving the application of a substantial amount of power and developing high pressure in the mix.

Mixing apparatus of various types has long been known. No mixer now available, however, has proved entirely satisfactory for handling certain classes of materials which are notoriously difficult to mix. Machines for handling asphalt-tile mixes, for example, have usually been adapted from machines originally designed for other materials and the inherent limitations thereof have prevented the processing of asphalt-tile mix with the speed and efficiency desired.

The apparatus used heretofore for heavy viscous mixes, such as that for making asphalt tile, have been subject to excessively high maintenance costs in regular operation and have required periodic reconstruction. The result of the operation of known machines, furthermore, has not been as good as desired from the standpoint of uniformity of dispersion of the various components of the mix, leaving out of consideration any question of efficiency or the time required. In certain mixing operations, moreover, different types of mixing action are desired at different stages of the processing. In the case of asphalt-tile mix, for example, the components of the base mix must first be uniformly interspersed. When this has been accomplished the mottle color is added and the mixing is continued until the mottle color is irregularly distributed, but the mixing must be stopped before the mottle color becomes uniformly blended with the base mix. Otherwise, the contrasting effect afforded by the mottle color would be lost. In other words, the base mix requires intensive mixing or mulling while the dispersion of the mottle color is best attained by a kneading action. Known mixers produce either a kneading action almost entirely or else a mulling or intensive mixing without any substantial amount of kneading.

I have invented a novel mixing apparatus which overcomes the above defects of previously known mixers and is characterized by further novel features and advantages which will be explained during the following detailed description of the invention. In a preferred embodiment, the apparatus of my invention comprises a mixing chamber including a pair of parallel substantially cylindrical compartments disposed side by side and in partly overlapping or intersecting relation, i.e., so that they open into each other throughout

2

a portion of their circumference. The chamber is preferably defined by spaced semi-cylindrical body casings and opposed reciprocable closures in the form of rams movable into and out of bridging position relative to the body casings. Spaced side members define the ends of the mixing chamber, the body casings extending between the side members and being secured thereto. Shafts disposed coaxially with the cylindrical compartments are provided with stirrers or mixing blades of novel construction adapted to effect a mulling or intensive mixing as well as a kneading action.

The axes of the compartments and the stirrer shafts lie in a plane inclined to the horizontal and the rams reciprocate in guide boxes along a path normal to said plane. The upper ram has a breaker block extending into the space between the paths of the outermost portions of the stirrers. A charging opening leading into the chamber is uncovered on retraction of the upper ram. The contents of the mixing chamber fall freely therefrom on retraction of the upper ram through an opening in the guide box of the latter. Access openings are provided at several points to facilitate cleaning of the interior of the chamber which must be done very thoroughly when changing colors. The lower body casing is also hingedly mounted on an upper spacer, further facilitating the cleaning.

A complete understanding of the invention may be had from the following detailed description in which additional novel features will be pointed out by reference to the accompanying drawings illustrating a preferred embodiment. Certain of the features disclosed herein, however, are the sole invention of Wendell W. Jones and are also disclosed and claimed in his copending application, Serial No. 625,827, filed October 31, 1948 for

40 Mixing apparatus.

In the drawings,

45 Figure 1 is an elevation of the apparatus;
Figure 2 is a side elevation taken from the left in Figure 1 with parts in section;

Figure 3 is a central section taken along the plane of line III—III of Figure 1;

Figure 4 is a transverse section through the upper ram taken along the plane of line IV—IV of Figure 5;

Figure 5 is a partial section taken longitudinally through the upper ram along the plane of line V—V of Figure 3;

50 Figures 6 and 7 are views corresponding respectively to Figures 4 and 5, showing sections

taken on line VI—VI of Figure 7 and line VII—VII of Figure 8;

Figure 8 is a partial section taken through the chamber on the plane of line VIII—VIII of Figure 2 which contains the axes of the stirrer shafts;

Figure 9 is a side elevation of one of the stirrers;

Figure 10 is an end elevation thereof taken from the right of Figure 9; and

Figures 11 through 20 are transverse sections taken through the stirrer along the planes designated by section lines correspondingly numbered in Roman numerals on Fig. 9.

Referring now in detail to the drawings, the apparatus of my invention includes spaced parallel side members 10 and 11 having feet 12 adapted to be bolted to a suitable foundation. Seats 13 are formed on the side plates for receiving and supporting thereon bearing pedestals 14 and 15. Stirrer shafts 16 and 17 are journaled in outboard roller bearings 18 and 19, respectively, carried by the pedestals 14 and 15. The shafts 16 and 17 are parallel and lie in a plane making an angle of about 45° with the horizontal. The shafts have stirrers or blades 20 and 21 thereon. These stirrers rotate with the shafts in the mixing chamber 22.

The mixing chamber 22 is defined by spaced upper and lower semi-cylindrical body casings 23 and 24 extending between the side members 10 and 11 and bolted thereto through flanges 25. The remainder of the wall of the mixing chamber is constituted by an upper ram 26 and a lower ram 27, both of which are normally positioned as shown in solid lines in Figure 3 but are retractable to the positions shown in chain lines. The ram 26 is rectangular in section, as shown in Figure 4, and reciprocates in a guide box defined by a spacer 28 and a cooperating spacer extension 23a integral with the upper body casing 23. The spacer 28 and extension 23a are bolted to the side members 10 and 11 through marginal flanges. A charging spout 29 is formed at the lower end of the extension 23a.

The body casings 23 and 24 have pipe coils 30 and 31 cast therein for the circulation of a heating or cooling medium. The coils terminate at terminal bosses 32, 33 and 34 which are tapped for the connection of supply and return pipes, hoses or the like. The terminal bosses on the casing 24 have locations slightly different from those on the casing 23 and are designated by the same reference numeral with the suffix *a*. By using two separate pipe coils for each casing, each coil extending around only half the circumference of the casing, it is possible to use pipe smaller than would otherwise be necessary to take care of steam condensation. It is desirable to keep the pipe size as small as possible to avoid weakening the casings.

The upper ram 26 has a breaker block 26a on the inner end thereof projecting into the space between the paths of the tips of the wings of the stirrers 20 and 21 to improve the mixing action thereof. These wings, to be further described later, force masses of the mix against the block 26a to divide them.

The ram 26 is reciprocated in its guide box by a hydraulic piston and cylinder 35. The inner end of the cylinder is secured to a plate 36 mounted on spaced bridging channels 37 extending between the side members 10 and 11 and secured thereto by angle brackets 38. A piston rod 39

extends from the cylinder and is threaded into a central boss 40 on the upper side of the ram. A pipe coil 41 is cast in the ram and inlet and outlet connections therefor are provided by pipes 42 and 43 threaded into the ram and slideable through holes in one of two plates 44 extending between the channels 37 on opposite sides of the cylinder 35. Terminal fittings 42a and 43a afford connections for flexible conduits such as hose.

10 The ram 26 has stop keys 45 which travel in slots 45a (see Figure 5) in the side members 10 and 11. The slots terminate at a point such as to arrest the inward movement of the ram in the position shown in solid lines in Figure 3. Shims 46 are secured to the inner ends of the lugs whereby the exact stopping point of the ram may be adjusted.

The lower body casing 24 is secured to a hinge bracket 47 by screws 47a extending through cooperating seating surfaces 48 and 49 on the plate and bracket. The bracket swings on a horizontal shaft 50 which passes through bearings 51 secured to the spacer 28 near the upper end thereof. When the bolts passing through the flange 25 of the casing 24 have been removed, the casing and bracket may be swung to the position shown in chain lines in Figure 3 by a fluid pressure cylinder-and-piston 52. The cylinder is trunnioned at 53 to the bracket and the piston rod is pivoted at 54 to the spacer 28.

It will ordinarily not be necessary to swing the casing 24 outwardly for routine inspection and maintenance. An opening is provided in the spacer 28 near the lower end for this purpose. 35 This opening is normally closed by a cover plate 55 hinged to the spacer 28 at 55a. The hinged mounting of the casing 24 is particularly advantageous for the purpose of thoroughly cleaning the interior of the apparatus when a change 40 of color of the base mix is contemplated.

The guide box for the lower ram 27 is defined by upper and lower spacers 56 and 57 extending between the side members 10 and 11, the spacers having flanges whereby they are bolted to the 45 side members. The lower ram, like the upper, is rectangular, and has a filler block 58 on the inner end thereof. It also has a pipe coil cast therein provided with supply and return connections similar to those described for the ram 50. The ram 27 is actuated by a cylinder-and-piston 59 mounted in the same manner as cylinder 35. The lower ram also has guide and stop keys 60 on opposite sides thereof as shown in Figure 7. These lugs travel in slots 61 in the 55 side members 10 and 11. Shims 62 are positioned in the slots for the same purpose as the shims 46 of the upper ram. Openings 62a in the side members (see Figure 7) give access to shims 62.

60 It will be observed that the structure of the two rams is similar in respect to the guide keys except that the lugs of the lower ram serve to guide the latter and maintain it properly aligned in its guide box, in addition to limiting upward 65 movement thereof. Thus the ram is maintained in proper relation to the body casings 23, 24 and spacers 56 and 57 even though it is out of engagement with all of them during a certain portion of its travel from normal position to retracted position.

The rams 26 and 27 have peripheral sealing grooves 26b and 27b adjacent their inner ends. Passages 23b and 23c in the body casing 23, communicate with said grooves permitting a fluid sealing medium such as grease to be delivered

thereto when the rams have been moved inwardly to the positions shown in solid lines in Figure 3. The grease may be delivered by any convenient dispensing system usually including a pump, a drive therefor and suitable connections between the pump and the inlet passages.

The spacers 56 and 57 terminate short of the semi-cylindrical body casings 23 and 24. This provides a discharge opening 63 on the lower side and an access or inspection opening 64 on the upper side of the mixer. It will be apparent that, because of the inclined position of the plane containing the axes of the shafts, the contents of the chamber 22 will fall practically straight down through the opening 63 when the ram 27 is retracted to the chain-line position.

The breaker block 26a is secured to the ram 26 by longitudinal screws 65 and transverse screws 65a, Fig. 3, passing through an outwardly extending flange 66 on each side of the block. The filler block 58 is similarly secured to the ram 27. Semi-cylindrical liners 67 are secured to the body casings 23 and 24 by screws 68 passing through outwardly extending flanges 69 (see Figure 8). The breaker and filler blocks and liners 67 preferably have an abrasion-resistant surface formed thereon.

The side members 10 and 11 are provided with removable end covers 70 and 71 overlying the ends of the chamber 22 and corresponding thereto in shape. The covers are secured to the side members by stud bolts 72 and are provided on the interior with removable liner plates 73 secured by screws 74 (see Figure 8). The removable end covers make possible the removal of the shafts and replacement of the stirrers without disturbing the side members or the body casings of the mixer. Stuffing boxes 75 are formed in the covers 70 and 71 for closing the clearance between them and the shafts 16 and 17, each stuffing box being provided with a gland 76.

Each of the shafts 16 and 17 has an axial bore 78 extending thereinto from the end opposite the driving end. A pipe 79 extends through a stuffing box 80 secured to the end of each shaft. A return pipe 81 extends through the pipe 79 and into the bore 78 from a fitting 82. Suitable connections (not shown) extend from the fittings 82 to a source of heating or cooling fluid. The fittings and pipes 79 and 81 remain stationary, of course, while the shafts and their stuffing boxes 80 revolve.

The stirrers 20 and 21 are keyed to the shafts 16 and 17 and the latter are preferably driven at slightly different speeds in opposite directions (as indicated by the arrows in Figure 3) by a suitable motor through a conventional pinion stand. Either the upper or lower shaft may be driven at the higher speed, preferably the lower one. As shown in Figures 9 through 20, each stirrer 20 comprises a body 83 having a bore 84 therethrough to admit the supporting shaft. Solid, massive wings 85 and 86 elongated axially, extend generally radially in opposite directions from the body portion 83. The wings are of unequal axial length and terminate in planes normal to the stirrer axis, the inner ends of the two wings lying substantially in a common plane. The overall length of the stirrer, as shown in Figure 8, is but slightly less than the axial length of the chamber 22. The wings 85 and 86 have a helical twist in the same direction longitudinally of the blade, but the pitch of the twist of the wings is not the same. The angle of the twist, furthermore, is not constant but increases pro-

gressively from the outer end of each wing toward the inner end thereof as shown in Figures 11 through 20. This improves the kneading action of the stirrers.

- 5 The two stirrers are oppositely disposed on their supporting shafts, as shown in Figure 8. The corresponding wings of the two stirrers thus do not overlap each other. The leading surfaces 87 and 88 of the wings are convex and the convexity decreases from the outer ends of the stirrer toward the common plane between the two wings, at least for a portion of the axial length of the wings. The decreasing convexity of the leading surfaces of the wings is clearly shown in Figures 11 through 20. As there illustrated, the convexity of the leading surface of wing 85 decreases from the plane on which the section of Figure 11 is taken, to that on which the section of Figure 12 is taken and so on through Figure 16. Correspondingly, the convexity of the leading surface of the wing 86 decreases between the plane on which the section of Figure 20 is taken and that on which the section of Figure 19 is taken and so on through Figures 18 and 17. 10 The minimum convexity of the longer wing 85 is greater than that of the shorter wing. In other words, the maximum radius of the leading surface of wing 85 is greater than that of the leading surface of the wing 86. 15 20 25 30 35 40
- The extreme outer tips of the wings are substantially flat throughout their length, as shown at 89 and 90, having a radius of curvature but slightly less than that of the casings 23 and 24. An intensive mixing or mulling action thus takes place between the wing tips and the inner surface of the mixing chamber 22. The other portions of the stirrer wings exert a kneading action, working the contents of the chamber 22 back and forth between the upper and lower cylindrical compartments thereof as well as axially thereof by reason of the helical twist of the wings.

The trailing surfaces 91 and 92 of the wings are substantially radial at least in their outer portions and slope gradually therefrom to the body portion of the stirrer. This provides sharp corners 93 which afford immediate release for the material being milled between the tips 89 and 90 and the surrounding walls of the chamber or the breaker block 26a.

It will be apparent from the foregoing that the invention provides a mixing apparatus of high efficiency compared to machines known previously, from the standpoint of the power consumed, the size of the charge, the time required for the mixing of the charge and the degree of intimacy of dispersion obtained. The apparatus is thus particularly suited for processing mixes used in the manufacture of asphalt tile but is also capable of handling other mixes such as those from which linoleum is made. The apparatus is characterized by easy and speedy charging and discharging. Ready access to all parts of the apparatus is afforded for inspection and cleaning. The apparatus requires but little maintenance even though the mixes it is intended to handle are quite abrasive. The wearing surfaces, such as the breaker and filler blocks, the liners 67, 73 are renewable, as well as the stirrer blades themselves.

By disposing the stirrer shafts in a plane at approximately 45° to the horizontal, the contents of the mixing chamber may be discharged in a straight drop through the opening 63 into a conveyor or a receptacle resting on the same floor

as the mixer itself. The lower ram serves to deflect the falling charge rearwardly. The breaker block 26, being on the upper ram, is entirely out of the way of the material being discharged. The filler block 58 on the lower ram occupies a space which tends to remain void in the operation of the mixer but does not interfere with the free discharge of the mixed material. The mixing action is not affected by arranging the breaker block on the upper ram because of the high pressure developed in the material during mixing as a result of the confinement of the charge in a space of fixed volume.

The upper ram carrying the breaker block against which the maximum mixing pressure is exerted is yieldably held in position by the pressure of the fluid in the cylinder 35. Should abnormal pressure be exerted against the breaker block, the ram 26 will yield sufficiently against the pressure in the cylinder 35 to afford relief.

The retraction of the upper ram preparatory to charging the mix into the chamber 22 affords extra space for accommodating the latter and the forward movement of the ram to its normal position after completion of the charging pushes the charge into the chamber. If desired, the bottom ram may also be retracted part way to provide increased space for the accommodation of the charge. For example, the ram 22 may be retracted to a position in which the block 58 closes the opening between the casings 23 and 24 to provide additional capacity for the reception of the ingredients to be mixed. The ram should not be retracted below this position until the mix is to be discharged from the machine. The hydraulic cylinder 59 may be provided with suitable controls for limiting retraction of the ram.

The upper ram 26 has a long skirt which permits the provision of an opening in the spacer 28 to give access to the interior of the chamber from above. This opening also permits the charging of large masses of material which cannot be fed through the spout 29. The opening 64 also permits access to the chamber from below for cleaning and inspection.

As previously mentioned, the removable end covers 70 permit the entire assembly of stirrers and supporting shafts to be withdrawn from the mixer after the shafts have been uncoupled from the drive mechanism, without completely dismantling the apparatus as is necessary in the case of mixers known heretofore.

The pipe coils cast in the body plates and rams permit the temperature of the mix to be controlled as desired during various stages of the mixing operation.

The removable wearing surfaces on the rams and semi-cylindrical body casings are secured through integral attaching flanges. This avoids the weakening of the blocks and liners which would result from holes extending directly through their exposed surfaces. The liners for the semi-cylindrical casings may be ground on the exterior for close contact with the plates themselves to assure good heat-transfer characteristics as well as adequate support. Creeping or wrinkling of the liners is prevented by making them in sections for the various portions of the chamber wall and with a substantial thickness. The liners, furthermore, may be removed without dismantling the entire machine. To remove the liner of the casing 24, it is only necessary to open the same with the hydraulic ram 52, and for removing the liner in the casing 23, it is only

necessary to remove the attaching means which secure the casing to the side members. The breaker block 26a, being independent of the other liner members, may be replaced oftener than the latter since it is subject to the most wear.

The stirrer blades are of such construction as to produce a combined mulling and kneading action. This is of particular importance in processing asphalt-tile mixes. The intensive mixing or mulling which occurs between the tips of the stirrer wings and the walls of the chamber and breaker block is highly effective in producing uniform dispersion of the components of the base mix. The kneading caused by the overlapping of cross currents produced by the helical twist and the unequal axial lengths of the wings is effective to produce the desired distribution of the mottle color quickly so that it does not become blended in the base mix. This practice gives a characteristic graining distinguished from that obtained in the practice of adding the mottle color at the mixing mill after the base components have been mixed in a conventional mixer. The kneading takes place as the charge is thrown back and forth by the wings of the stirrer as a result of the break or discontinuity between the wings at their adjacent ends. This also causes a shearing action which is desirable in the case of linoleum mixes for breaking up the lumps therein and, aided by the speed differential between the blades, prevents the setting up of a consistent repetitive motion of the mix. The massive character of the stirrer wings stiffens the supporting shafts and limits their deflection to values such that they may satisfactorily be journaled in roller bearings. The mulling action of the tips of the blade wings is such that the desired amount of heat is generated in most cases by friction in the mix, but the coils 30 and 31 permit the supply of additional heat from an external source, if desired, as well as the removal of excess heat when necessary.

Although I have illustrated and described herein but a preferred embodiment of my invention, it will be understood that changes in the construction and arrangement of parts disclosed may be made without deviating from the spirit of the invention or the scope of the appended claims.

I claim:

- 50 1. A mixer blade comprising a body portion having a pair of axially elongated, substantially oppositely extending, generally radial wings, each presenting a leading working surface which is convex for the greater portion, at least, of its axial length and has a helical twist longitudinally of the blade, the convexity of the portion of said working surface of each wing adjacent the leading edge thereof decreasing progressively for a portion, at least, of the axial length of each wing from the outer end thereof toward the inner end thereof where it adjoins the other wing.
- 55 2. A mixer blade comprising a body portion having a pair of axially elongated, substantially oppositely extending, generally radial wings of unequal length, each presenting a leading working surface which is convex for the greater portion, at least, of its axial length and has a helical twist longitudinally of the blade, the convexity of the portion of said working surface of each wing adjacent the leading edge thereof decreasing progressively for a portion, at least, of the axial length of each wing from the outer end thereof toward the inner end thereof where it adjoins the other wing.
- 60 3. The apparatus defined by claim 1 charac-

terized by the extreme tips of said wings having a substantially flat portion extending circumferentially on a radius smaller than that of said compartment, and extending substantially the full length of the wings.

4. The apparatus defined by claim 2 characterized by the maximum radius of curvature of the longer wing being greater than that of the shorter wing.

5. A mixer blade comprising a body portion having a pair of axially elongated, substantially oppositely extending, generally radial wings, each wing presenting a leading working surface which is convex for the greater portion, at least, of its axial length and has a helical twist longitudinally of the blade, the angle of said twist increasing for a portion, at least, of the axial length of each wing from the outer end thereof toward the inner end thereof where it adjoins the other wing.

6. A mixer comprising a substantially closed mixing chamber consisting of two parallel substantially cylindrical compartments opening into each other at their adjacent sides, spaced casings comprising the sides of said compartments, a movable closure adapted to be moved into registry with the spaced casings to complete one side of said compartments, a breaker block attached to said closure and projecting downwardly into and between the compartments, a stirrer blade journaled axially in each of said compartments and adapted to operate in such manner that the leading surfaces of each blade rotate toward the breaker block, said breaker block forming the adjacent portions of the upper sides of said compartments and serving to divide masses of material carried upwardly against it by said blades, said compartments being provided with a discharge opening opposite said breaker block, and a movable closure for said opening.

7. A mixer comprising a substantially closed mixing chamber including two parallel substantially cylindrical compartments opening into each other along their adjacent sides, said compartments having axes substantially parallel and horizontal and lying in a single plane inclined to the horizontal, spaced casings comprising the sides of said compartments, a movable closure adapted to be moved into registry with the edges of said spaced casings to complete one side of said compartments, and means for advancing and retracting said closure in a direction normal to said single plane.

8. A mixer comprising a substantially closed mixing chamber including two parallel substantially cylindrical compartments opening into each other along the adjacent sides thereof and having substantially parallel horizontal axes lying in a single plane inclined to the horizontal, a breaker block in the upper portion of said chamber and partially between said compartments, a mixing blade axially disposed in each of said compartments and adapted to operate in such manner that the leading surfaces of each blade rotate toward the breaker block thereby serving to divide masses of material carried against it by said blades, and a movable closure for said compartments adapted to be advanced and retracted in a direction normal to said single plane.

9. A mixer comprising a substantially closed mixing chamber consisting of two parallel substantially cylindrical compartments opening into each other at their adjacent sides and having axes substantially parallel and horizontal and lying in a single plane inclined to the horizontal, a breaker block projecting downwardly into and be-

tween the compartments, a stirrer blade journaled axially in each of said compartments and adapted to operate in such manner that the working surfaces of each blade rotate toward the breaker block, said breaker block forming the adjacent portions of the upper sides of said compartments and serving to divide masses of material carried upwardly against it by said blades, said compartments being provided with a discharge opening, and a movable closure for said opening.

10. A mixer comprising a substantially closed mixing chamber including two parallel substantially cylindrical compartments opening into each other at their adjacent sides, the axes of said compartments being substantially parallel and horizontal and lying in a single plane inclined to the horizontal, a breaker block projecting downwardly into and between the compartments, a stirrer blade journaled axially in each of said compartments and adapted to operate in such manner that the working surfaces thereof lead as the blade rotates toward the breaker block, said breaker block forming the adjacent portions of the upper sides of said compartments and serving to divide masses of material carried upwardly against it by said blades, said compartments being provided with a discharge opening opposite said breaker block, and a movable closure for said discharge opening forming the adjacent portions of the lower sides of said compartments.

11. A mixer comprising a substantially closed mixing chamber including two parallel substantially cylindrical compartments opening into each other at their adjacent sides, spaced casings forming the outside of said compartments, guide members extending upwardly adjacent the upper sides of said compartments, a ram which slidably engages said guide members, a breaker block attached to the lower portion of said ram, means for advancing and retracting said ram and adapted to yieldably maintain said ram in advance position in such manner that the breaker block projects downwardly into and between the compartments and constitutes a closure continuation of the inner upper surfaces thereof, a stirrer blade journaled axially in each of said compartments and adapted to operate in such manner that the working surfaces thereof lead as the blade rotates toward the breaker block, said compartments being provided with a discharge opening, and a movable closure for said opening.

12. A mixer comprising a substantially closed mixing chamber including two parallel substantially cylindrical compartments opening into each other along their adjacent sides, spaced casings forming the outsides of said compartments, movable closures substantially forming the remainder of the upper and lower sides of said compartments, a breaker block affixed to the upper movable closure, blades positioned coaxially in said compartments and adapted to operate in such manner that their respective working surfaces lead during rotation toward said breaker block and hinged means adapted to swing one of said spaced casings away from its related compartment to afford access to or discharge from said chamber.

13. A mixer comprising a substantially closed mixing chamber, said chamber having two parallel substantially cylindrical compartments opening into each other along their adjacent sides and having their axes substantially parallel and horizontal and lying in a single plane inclined to the horizontal, a retractable ram adjacent the upper sides of said compartments and adapted to oper-

ate in a direction perpendicular to said single plane, a breaker block carried on the lower end of said ram and adapted when the ram is in advanced position to constitute the upper closure for said compartments, said breaker block projecting downwardly into and between said compartments, a movable closure substantially across the chamber from said breaker block and adapted to constitute the lower closure for said compartments, said breaker block and said movable closure having, when in closed position, inner surfaces continuous with the remainder of the inner surfaces of said compartments, means affording access to the interior of said ram and breaker block assembly, a stirrer blade coaxially positioned in each compartment and adapted to rotate so that its working surfaces lead as it moves toward said breaker block, means for retracting said ram and breaker block to permit charging material into said compartments for mixing, and means for opening said movable closure to discharge the contents of said compartments.

14. A mixer comprising a substantially closed mixing chamber, said chamber having two parallel substantially cylindrical compartments opening into each other along their adjacent sides and having their axes substantially parallel and horizontal and lying in a single plane inclined to the horizontal, a retractable ram adjacent the upper sides of said compartments and adapted to operate in a direction perpendicular to said single plane, a breaker block carried on the lower end of said ram and adapted when the ram is in advanced position to constitute the upper closure for said compartments, said breaker block projecting downwardly into and between said compartments, a movable closure substantially across the chamber from said breaker block and adapted to constitute the lower closure for said compartments, said breaker block and said movable closure having, when in closed position, inner surfaces continuous with the remainder of the inner surfaces of said compartments, a stirrer blade coaxially positioned in each compartment and adapted to rotate so that its working surfaces lead as it moves toward said breaker block, means for retracting said ram and breaker block to permit charging material into said compartments for mixing, and means for opening said movable closure to discharge the contents of said compartments.

15. A mixer comprising a substantially closed mixing chamber including opposed substantially semi-cylindrical casings, side members disposed at the ends of said casings, closures for the openings between the said casings and side members and adapted to define thereby a pair of parallel substantially cylindrical compartments opening into each other along the adjacent sides thereof, said compartments having their axes in substantially horizontal spaced parallel relation, said side members having openings in alignment with the axes of said compartments, covers removably secured to said side members overlying said openings, a stirrer blade on a shaft positioned coaxially in each compartment, and bearings to support said shafts, said bearings being spaced outwardly of and apart from the side members whereby said stirrer blades may be removed axially through the openings in said side members after removal of said covers secured thereto.

16. A mixer comprising a substantially closed mixing chamber including opposed substantially semi-cylindrical casings, side members disposed at the ends of said casings, closures for the upper

and lower openings between said casings and the side members, said closures adapted to define thereby a pair of parallel substantially cylindrical compartments opening into each other along one side and having their axes in substantially horizontal spaced parallel relation, said side members having openings in alignment with the axes of said compartments, covers removably secured to said side members overlying said openings, a shaft positioned coaxially in each compartment and extending through said covers, a mixing blade on each shaft, a seal surrounding each shaft in the area of the passage of the shaft through the said covers and adapted to be attached to the said covers for sealing the clearance between said shafts and said covers, bearings for the support of each shaft spaced outwardly of and apart from said side members whereby said stirrer blades may be removed axially through one of the openings in said side members after removal of the cover secured thereto.

17. A mixer comprising a substantially closed mixing chamber including opposed substantially semi-cylindrical casings, side members disposed at the ends of said casings, upper and lower closure members disposed between said casings and said side members to complete the said chamber, stirrer blades disposed in said chamber coaxially with the axes of said casings, a shaft supporting each stirrer blade, journaling means for said shafts spaced outwardly of and apart from said side members, said side members having openings through which said stirrer blades may be removed axially, removable covers for said openings and surrounding said shafts, and removable wearing surfaces in said chamber and on said covers.

18. A mixer comprising a substantially closed mixing chamber, said chamber having two parallel substantially cylindrical compartments opening into each other along their adjacent sides and having their axes substantially parallel and horizontal and lying in a single plane inclined to the horizontal, substantially semi-cylindrical casings in spaced relationship forming the sides of said compartments, side members disposed at the ends of said compartments and having openings therein in registry with said compartments, a retractable ram adjacent the upper sides of said compartments and adapted to operate in a direction perpendicular to said single plane, a breaker block carried on the lower end of the said ram and adapted when the ram is in advanced position to constitute the upper closure for said compartments between said casings and said side members, said breaker block projecting downwardly into and between said compartments, a movable closure substantially across the chamber from said breaker block and adapted to constitute the lower closure for said compartments between said casings and said side members, said breaker block and said movable closure having, when in closed position, inner surfaces continuous with the remainder of the inner surfaces of said casings to form the inner surfaces of said compartments, a stirrer blade coaxially positioned in each compartment and adapted to rotate so that its working surfaces lead as it moves toward said breaker block, a supporting shaft for each stirrer blade, removable covers for said openings in said side members through which said shafts extend, journaling means for said shafts independent of and spaced away from said side members and covers, means for swinging one of said casings a limited distance from

13

said compartments to open said compartments, means for retracting said ram and breaker block to permit charging material into said compartments for mixing, and means for opening said movable closure to discharge the contents of said compartments.

19. A mixer comprising a substantially closed mixing chamber, said chamber having two parallel substantially cylindrical compartments opening into each other along their adjacent sides and having their axes substantially parallel and horizontal and lying in a single plane inclined to the horizontal, substantially semi-cylindrical casings in spaced relationship forming the sides of said compartments, side members disposed at the ends of said compartments and having openings therein in registry with said compartments, a retractable ram adjacent the upper sides of said compartments and adapted to operate in a direction perpendicular to said single plane, a breaker block carried on the lower end of the said ram and adapted when the ram is in advanced position to constitute the upper closure for said compartments between said casings and said side members, said breaker block projecting downwardly into and between said compartments, a movable closure substantially across the chamber from said breaker block and adapted to constitute the lower closure for said compartments between said casings and said side members, said breaker block and said movable closure having, when in closed position, inner surfaces continuous with the remainder of the inner surfaces of said casings to form the inner surfaces of said compartments, adjustable means for limiting the travel of the said breaker block and movable closure upon closure to insure registry of the inner surfaces thereof with the inner surfaces of said compartments, a stirrer blade coaxially positioned in each compartment and adapted to rotate so that its working surfaces lead as it moves toward said breaker block, a supporting shaft for each stirrer blade, removable covers for said openings in said side members through which said shafts extend, journaling means for said shafts independent of and spaced away from said side members and covers, means for swinging one of said casings a limited distance from said compartments to open said compartments, means for retracting said ram and breaker block to permit charging material into said compartments for mixing, and means for opening said movable closure to discharge the contents of said compartments.

20. A mixer comprising a substantially closed mixing chamber having two parallel substantially cylindrical compartments opening into each other along their adjacent sides, a breaker block positioned in the upper portion of said chamber and partially between said compartments, said compartments being provided with a discharge opening opposite said breaker block, a movable closure for said opening, and a mixing blade positioned axially in each of said compartments and adapted to operate in such manner that a working surface of each blade leads during the rotation of such blade toward the breaker block, said working surface being convex for the greater portion, at least, of its axial length and having

14

a helical twist longitudinally of the blade, the convexity of the portion of said working surface of each wing adjacent the leading edge thereof decreasing progressively for a portion, at least, of the axial length of each wing from the outer end thereof toward the inner end thereof where it adjoins the other wing.

21. A mixer comprising a substantially closed mixing chamber having two parallel substantially cylindrical compartments opening into each other along their adjacent sides, a breaker block positioned in the upper portion of said chamber between said compartments, said compartments being provided with a discharge opening opposite said breaker block, a movable closure for said opening, and a mixing blade positioned axially in each of said compartments and adapted to operate in such manner that a working surface of each blade leads during the rotation of such blade toward the breaker block, said working surface being convex for the greater portion, at least, of its axial length and having a helical twist longitudinally of the blade, the convexity of the portion of said working surface of each wing adjacent the leading edge thereof decreasing progressively and the angle of twist of each wing increasing, such decrease in convexity and increase in angle of twist extending for a portion, at least, of the axial length of each wing from the outer end thereof toward the inner end thereof where it adjoins the other wing.

22. A mixing blade comprising a body portion having a pair of axially elongated, substantially oppositely extending, generally radial wings, each wing presenting a leading working surface which is convex for the greater portion, at least, of its axial length and has a helical twist longitudinally of the blade, the convexity of the portion of said working surface of each wing adjacent the leading edge thereof decreasing progressively and the angle of twist of each wing increasing progressively, such decrease in convexity and increase in angle of twist extending for a portion, at least, of the axial length of each wing from the outer end thereof toward the inner end thereof where it adjoins the other wing.

Certificate of Correction

Patent No. 2,495,241

January 24, 1950

LE ROY EABY

It is hereby certified that errors appear in the printed specification of the above numbered patent requiring correction as follows:

Column 1, line 20, for the word "casts" read *costs*; column 2, line 23, for "upper" read *lower*; line 39, for "October 31, 1948" read *October 31, 1945*; column 8, line 70, for "descreasing" read *decreasing*;

and that the said Letters Patent should be read with these corrections therein that the same may conform to the record of the case in the Patent Office.

Signed and sealed this 9th day of May, A. D. 1950.
